DESULFURIZATION OF OILS

Bernard L. Evering, Chicago, Ill., Arthur P. Lien, Hammond, Ind., and James M. Page, Jr., Chicago, Ill., assignors to Standard Oil Company, Chicago, Ill., a corporation of Indiana

Application May 19, 1945, Serial No. 594,610

4 Claims. (Cl. 196—31)

1

The present invention pertains to improvements in the refining of non-viscous hydrocarbon oils and more particularly pertains to the desulfurization of non-viscous hydrocarbon oils, such as naphthas, gasoline and the like.

It is known that hydrocarbon oils, such as mineral oils, for example crude oils, reduced crudes, lubricating oils, furnace and Diesel oils and naphthas including those within the gasoline boiling range, can be desulfurized by extraction with a combination of anhydrous liquid hydrogen fluoride and boron fluoride. Thus, United States Patent 2,343,841 issued to R. E. Burk March 7, 1944, teaches the desulfurization of crude petroleum oil or fractions thereof by extraction with a mixture of liquid HF and BF₃. The solvent extraction of petroleum oils with a mixture of anhydrous liquid HF and BF₃ possesses the undesirable feature in that any aromatics present in the stock extracted are also removed as part of the extract. The removal of aromatics from various petroleum fractions may not be undesirable, but for the treatment of certain fractions, particularly the lighter fractions boiling within the naphtha distillation range and up to a maximum distillation temperature at about atmospheric pressure of about 450° F., it is highly desirable to retain in such fractions any aromatics which may be contained therein.

It is an object of the present invention to provide a solvent extraction method of desulfurizing non-viscous petroleum fractions without the removal of substantial quantities of aromatics. Another object of the invention is to provide an improved process of solvent extracting non-viscous petroleum fractions with a solvent which is selective to the removal of sulfur from such fractions. Another object of the invention is to provide an improved solvent extraction process for the removal of sulfur and sulfur-containing constituents from petroleum-naphtha boiling within the motor fuel distillation range. Another object of the invention is to provide an improved method for the desulfurization of petroleum naphthas. Still another object of the invention is to provide an improved process for the removal of sulfur without the removal of substantial quantities of aromatics from petroleum naphthas. Other objects and advantages of the present invention will become apparent from the following description thereof read in conjunction with the accompanying drawing in which Figure 1 is a flow diagram of a preferred method of carrying out the present invention, and Figure 2 is a flow diagram of

2

a modified method of treating the initial feed stock.

In accordance with the present invention the foregoing objects can be attained by extracting 5 non-viscous petroleum oil fractions, such as naphthas and motor fuels, with a solvent consisting of anhydrous liquid hydrogen fluoride. The quantity of anhydrous liquid hydrogen fluoride employed should be sufficient to give a diphasic 10 separation, and can vary from about 10 volume percent to about 100 volume percent or more and preferably from about 15 volume percent to about 50 volume percent, although for certain types of oils as little as 5 volume percent or less 15 will give a diphasic separation. Temperatures of from about 0° F. to about 212° F. and preferably from about 32° F. to about 100° F. can be employed. However, if desired somewhat higher temperature, for example temperatures of about 20 400° F. can be used, in the manner hereinafter described. A pressure sufficient to maintain the solvent in the liquid phase is preferably maintained in the extraction chamber. A contact time of from about one minute to about 120 minutes 25 or more can be employed, although a contact time of from about 5 minutes to about 60 minutes is usually sufficient.

A method for practising the present invention is illustrated by the following example:

30 Referring to Figure 1, a sulfur-containing gasoline fraction having an initial boiling point of about 215° F. and an end point of about 420° F. by A. S. T. M. distillation, is introduced through line 10 into the bottom portion of the extractor 35 11, while liquid anhydrous hydrogen fluoride is introduced into the upper portion of the extractor through a line 12. The extractor 11 is suitably a packed column in which anhydrous hydrogen fluoride and the sulfur-containing feed stock are 40 contacted countercurrently, although other suitable means of obtaining intimate contact can be employed. The extractor 11 is operated at a temperature within the range of from about 0° F. to about 212° F. and preferably from about 32° F. to about 100° F., and under sufficient pressure to maintain the reactants in the liquid phase.

A raffinate substantially free of sulfur or having a sulfur-content substantially lower than that 50 of the feed stock, is removed from the extractor 11 through a line 13 and introduced into a settler 14, wherein any entrained HF or HF extract is settled out and returned through a line 15 to the extractor 11 via line 58. The raffinate containing 55 dissolved hydrogen fluoride in the settler 14 is

introduced through a line 16 and a pump 16a into the bottom portion of a stripper 17. Even when the overhead from the extractor 11 does not contain entrained HF, it is advantageous to employ settler 14 to function as an accumulstator and to protect against surges. Gases in settler 14 can be vented through a vent (not shown) or withdrawn through lines 18, 19 and 12, and returned to the extractor 11. If desired, the overhead from the extractor 11 can be passed through lines 13 and 13a to the stripper 17, thereby by-passing settler 14.

The raffinate product stream introduced into the stripper 17 is heated by suitable means, such as by a heating coil 20, to remove hydrogen fluoride from the product. Stripper 17 is operated under pressure and temperature conditions to assure the removal of substantially all of the hydrogen fluoride from the raffinate product. These conditions will vary over a wide range depending upon the stock being treated. For example, when a gasoline fraction having the aforementioned distillation characteristics is employed as the feed stock, temperatures within the range of from about 200° F. to about 450° F., and preferably from about 300° F. to about 400° F. and pressures from about 5 to about 150 pounds per square inch, and preferably from about 25 to about 100 pounds per square inch are suitably employed. Hydrogen fluoride separated in the stripper 17 is removed overhead through a line 21 and can be directed through line 22 to the hydrogen fluoride storage tank 23; or can be recycled through lines 24, 25, 19 and 12 to the extractor 11. Makeup hydrogen fluoride can be introduced into the system through line 23a.

The bottoms from the stripper 17 comprising a substantially desulfurized raffinate product substantially free of hydrogen fluoride can normally be removed from the stripper 17 through a line 26 and passed through a conventional bauxite tower 21, or other suitable system to insure the removal of fluorides, such as hydrogen fluoride and alkyl fluorides which may be contained in the desulfurized product from the stripper 17. The desulfurized product, substantially free of fluorides, is removed from the tower 27 through a line 28.

When a stock, such as gasoline, being desulfurized contains butanes, an azeotrope with the hydrogen fluoride may be formed. To separate the components of the azeotrope the butane-hydrogen fluoride azeotrope is passed overhead from stripper 17 through lines 21, 22, valved line 29 and a condenser 30 to a settler 31 which is operated at as low a temperature as can be obtained with available cooling water, preferably at a temperature well below 100° F. The condensed azeotrope separates into a heavier hydrogen fluoride layer which is withdrawn through lines 32 and 22 to the hydrogen fluoride storage tank 23. The upper butane layer is returned through pump 33 and line 34 as reflux to the top of stripper 17. Lighter gases and some propane may be vented from the settler 31 through a line 35.

The hydrogen fluoride extract from the extractor 11 is passed through a line 36 to a hydrogen fluoride recovery tower 37, the bottom temperature of which is maintained at a temperature between about 100° F. to 150° F. by heating coil 38, to drive off the unbound hydrogen fluoride. The hydrogen fluoride from the tower 37 is passed through lines 39 and 40 through a condenser 41 to a receiver 42. If the extract from

the extractor 11 contains some low boiling hydrocarbon fractions, the overhead from the tower 37 is first fractionated by suitable means (not shown) to fractionate the hydrogen fluoride from the low boiling hydrocarbons before the former is recycled to the hydrogen fluoride storage tank 23. The bottom from the tower 37 is passed through a line 43 to a second hydrogen fluoride recovery tower 44, provided with suitable heating means, such as a heating coil 45 to maintain a bottom temperature therein of from about 150° F. to about 500° F. to decompose the chemically bound hydrogen fluoride which is passed from tower 44 through lines 46, 40 and condenser 41 to the receiver 42, while the extract, substantially free of hydrogen fluoride, but having a high sulfur content is removed from the tower 44 through a line 47.

Some water enters the system through the feed 20 stock and makeup hydrogen fluoride. To prevent this water from building up in the system, it is removed by by-passing a portion of the recycled hydrogen fluoride from towers 37 and 44 through a line 48 to a hydrogen fluoride-water azeotrope 25 silver-lined distillation tower 49, provided with a suitable heating means 50 in the bottom portion thereof. Anhydrous hydrogen fluoride is removed overhead from the tower 49, through lines 51 and 40 and condenser 41 to receiver 42, and aqueous hydrogen fluoride is removed from the 30 bottom of tower 49 through a line 52. A portion of the anhydrous hydrogen fluoride in receiver 42 is returned through line 53 and pump 54 to the top of tower 49 to serve as reflux. The hydrogen fluoride in receiver 42 can be passed via pump 55 and a line 56 to the storage tank 23.

A portion of the extract from extractor 11 may, if desired, be recycled to the extractor 11 through lines 57 and 58. It is to be understood that while 40 we have shown a single extractor in Figure 1, a plurality of extractors may be used; also HF extract can be recycled to the same extractor or to different extractors.

In the foregoing example we have described extraction at a temperature up to about 212° F. Under some conditions it may be desirable to carry out a conversion and/or an extraction at an elevated temperature above about 212° F., for example about 300° F. to 400° F., followed by an extraction at a lower temperature, for example, about 0° F. to about 212° F., preferably about 75° F. Thus, the sulfur-containing feed stock can be contacted with liquid anhydrous hydrogen fluoride at the elevated temperature, say about 400° F. and the hydrogen sulfide, resulting from the conversion of some of the sulfur compounds along with any lighter hydrocarbons, after cooling, is flashed off. The resultant mixture of hydrogen fluoride and treated product 50 can then be cooled to the final extracting temperature, for example about 75° F., additional hydrogen fluoride added if necessary and the extraction process proceeding as above described. If desired, a diphasic separation can be made after 55 contacting at the elevated temperature and cooling to the lower temperature, the extract layer removed, additional hydrogen fluoride added and an extraction made at a temperature of from about 0° F. to about 212° F., preferably about 75° F. as above described. This combined conversion-extraction process results in a very effective desulfurization of the stock so treated.

This modified high temperature treatment of the initial feed stock can be carried out as follows: Referring to Figure 2 the feed stock, containing

sulfur, and hydrogen fluoride are introduced into the extractor 11 through lines 10 and 12 respectively, and the mixture heated to a temperature above about 212° F., for example from about 300° F. to 400° F. The heated mixture from the extractor 11 is passed through line 13 and a cooler 13b to a flash drum 14a wherein hydrogen sulfide resulting from the conversion of the sulfur compounds in the feed stock, along with light hydrocarbon, are flashed off through vent 14b. The mixture of hydrogen fluoride and treated product in flash drum 14a is passed through line 15a and cooler 15b to extractor 11a and mixed with additional hydrogen fluoride introduced through line 12a. A pressure sufficient to keep the hydrogen fluoride and hydrocarbon oil in the liquid phase is maintained within the extractor 11a. The mixture of hydrogen fluoride and oil in extractor 11a is allowed to separate into a raffinate phase and an extract phase, and the raffinate withdrawn from the extractor 11a through line 11b passed to settler 14 (Figure 1) and thereafter processed as hereinbefore described in connection with Figure 1. The extract is withdrawn from the extractor 11a through line 36a and introduced via line 36 to the hydrogen fluoride recovery tower No. 1 (shown in Figure 1) and thereafter processed as hereinbefore described.

Alternatively, the mixture of oil and hydrogen fluoride in extractor 11a may be agitated without added hydrogen fluoride and then separated into a raffinate phase and extract phase. The raffinate phase may then be withdrawn through line 11a and the extract phase through line 36a and processed as above described. If desired, the extract in the extractor 11b may be withdrawn through line 36a, additional hydrogen fluoride introduced into the extractor 11a through line 12a, the mixture agitated and then settled to obtain a further raffinate phase and extract phase which may then be withdrawn from extractor 11a and processed in the manner hereinbefore described.

The effectiveness of anhydrous liquid hydrogen fluoride as a solvent extractant for the removal of sulfur from non-viscous hydrocarbon oils is demonstrated by the data in Table I. These data were obtained by extracting a heavy naphtha cut having a boiling range of from 218° F. to 416° F. from a high sulfur crude oil with varying quantities of anhydrous liquid HF at a temperature of about 80° F.

TABLE I
Sulfur extraction of heavy naphtha

Run No.	cc. HF per Liter	Raffinate, Wt. percent S	Degree of Sulfur Ext., Wt. percent	Extract Layer Wt. percent S	Treating Loss, Wt. percent ¹	Octane No., CFR-M		
						Clear	1 cc.	3 cc.

3.	200	0.03	92.0	16.2	2.18	40.7	52.1	62.1

¹ Based on S Analyses.

The above data show a substantially complete removal of sulfur from heavy naphtha. Although the raffinate show a slightly lower clear octane rating than the feed, better lead responses are obtained on the desulfurized stocks. The low treating losses reflect a substantially negligible extraction of aromatics from the feed stock.

The advantage of extracting non-viscous hydrocarbon oils of the type herein-described with hydrogen fluoride alone over using a mixture of

hydrogen fluoride and boron fluoride is clearly shown by the data in Table II. These data were obtained by extracting at a temperature of about 80° F. and with a contact time of about 60 minutes a heavy naphtha having initial distillation of about 218° F. and an end point of about 416° F. from Slaughter crude, using as the solvent extractant anhydrous liquid hydrogen fluoride alone, and anhydrous liquid hydrogen fluoride in combination with boron fluoride. Run 1 was made by extracting the heavy naphtha with a mixture of 400 cc. of hydrogen fluoride per liter of naphtha and 67 grams of boron fluoride per liter of naphtha which gave an initial boron fluoride pressure of 55 pounds per square inch in the extractor. Run 2 was made under identical conditions as in Run 1 except that the boron fluoride was omitted.

TABLE II

Run No.	HF	BF ₃	Spec. Disp. Raffinate	Octane No.		Trtg. Loss Wt. Percent
				Clear	3 cc.	
Feed				116	41.9	54.2
1.	400	67	104	35.6	60.7	15.1
2.	400	—	116	40.3	61.5	2.3

Comparison of the specific dispersions of the feed stock and the raffinate from Runs 1 and 2 show that with the hydrogen fluoride alone the extraction of aromatics is substantially negligible, whereas with the mixture of hydrogen fluoride and boron fluoride a high degree of aromatic extraction took place. The specific dispersion value indicates the degree of aromaticity of the extracted naphtha. The specific dispersion value of 116 in the feed and in Run 2 indicates substantially no removal of aromatics from the feed stock, whereas the specific dispersion value of 104 for the raffinate in Run 1 indicates a substantial degree of aromatic extraction from the feed stock. The method of determining the specific dispersion is described in the article "Quantitative Determination of Aromatic Hydrocarbons by a New Method" by A. V. Grosse and R. C. Wackher, published in the Industrial and Engineering Chemistry Analytical Edition, volume 11, No. 11 (November 15, 1939) pages 614 to 624 inclusive. As shown by the date in Table II, the effect of aromatic removal is reflected in the high

treating loss, a treating loss of 15.1% being obtained when the combination of hydrogen fluoride and boron fluoride is used as compared to a treating loss of only 2.3% when hydrogen fluoride alone was used as the extractant. A greater removal of aromatics is also reflected in the antiknock rating of the motor fuel. It will be noted that in Run 1 there was obtained a lowering of the clear octane number of from 41.9 for the feed stock to 35.6, whereas when hydrogen

fluoride alone was employed as the extractant there was a lowering of the clear octane number of only 1.6; namely, from 41.9 to 40.3. It will also be noted that even with the addition of 3 cc. of lead tetraethyl, the octane number was still lower for the raffinate obtained in the hydrogen fluoride and boron fluoride treatment than for the raffinate obtained in the extraction using hydrogen fluoride alone.

The present invention is not to be confused with prior art processes of treating petroleum stocks with liquid hydrogen fluoride, wherein the hydrogen fluoride is employed as a treating agent in amounts and under conditions which do not permit stratification into a raffinate fraction and an extract fraction. The process of the herein-described invention in contradistinction to prior art processes provides a process whereby the sulfur-containing constituents of the non-viscous hydrocarbon oils are extracted with a sufficient quantity of anhydrous liquid hydrogen fluoride to permit stratification of a substantially sulfur-free raffinate and a sulfur-containing extract, the solvent in both the raffinate and the extract being recovered and recycled for further extraction of the feed stock.

In addition to the removal of sulfur from non-viscous hydrocarbon oils, extraction with liquid anhydrous hydrogen fluoride also effectively removes nitrogen and/or oxygen compounds from such stocks.

The term "non-viscous hydrocarbon oil" as used herein and in the appended claims means a hydrocarbon oil less viscous than hydrocarbon oils within the lubricating oil range; namely, those having a Saybolt Universal viscosity at 100° F. of less than about 60 seconds.

It is to be understood that while certain preferred embodiments of the invention have been herein-described, the invention is not to be limited thereto, but includes within its scope such modifications as fairly come within the spirit of the appended claims.

We claim:

1. The method of selectively desulfurizing a non-viscous aromatic-containing hydrocarbon oil comprising contacting said oil with a solvent consisting of liquid anhydrous hydrogen fluoride at a temperature within the range of about 300° F. to about 400° F., flashing off any hydrocarbon gases and hydrogen sulfide resulting from the conversion of sulfur compounds in said oil, cooling the flashed mixture of hydrocarbons and hydrogen fluoride to a temperature of from about 0° F. to about 212° F., contacting the cooled mixture with additional liquid anhydrous hydrogen fluoride while maintaining a pressure sufficient to maintain the solvent and hydrocarbon oil in the liquid phase, permitting the mixture of said oil and liquid hydrogen fluoride to stratify into an aromatic-containing raffinate phase substantially free of sulfur and a sulfur-containing extract phase, separating said phases and removing the hydrogen fluoride from said phases.

2. The method of selectively desulfurizing a non-viscous aromatic-containing hydrocarbon oil comprising treating said oil with liquid anhydrous hydrogen fluoride at a temperature with-

in the range of about 300° F. to about 400° F., flashing off any hydrocarbon gases and hydrogen sulfide resulting from the conversion of sulfur compounds in said oil, cooling the flashed mixture to a temperature of from about 0° F. to about 212° F., agitating said mixture at said lower temperature while maintaining a pressure sufficient to maintain the hydrogen fluoride and said oil in the liquid phase, permitting the mixture to separate into an aromatic-containing raffinate phase substantially free of sulfur and a sulfur-containing extract phase and separating said phases.

3. The method of selectively desulfurizing a non-viscous aromatic-containing hydrocarbon oil comprising contacting said oil with a solvent consisting of liquid anhydrous HF at a temperature within the range of about 300° F. to about 400° F., flashing off any hydrocarbon gases and hydrogen sulfide resulting from the conversion of the sulfur compounds in said oil, cooling the flashed mixture to a temperature of about 0° F. to about 212° F., permitting the mixture to separate into a raffinate layer and an extract layer, removing the extract layer, contacting the raffinate layer with additional liquid anhydrous HF at a temperature of from about 0° F. to about 212° F. under a pressure sufficient to maintain the solvent and oil in the liquid phase, permitting the mixture to separate into an aromatic-containing raffinate phase substantially free of sulfur and a sulfur-containing extract phase and separating said phases.

4. The method of selectively desulfurizing a non-viscous aromatic-containing hydrocarbon oil comprising contacting said oil with a solvent consisting of liquid anhydrous hydrogen fluoride at a temperature within the range of about 300° F. to about 400° F., cooling the mixture to a temperature of from about 0° F. to about 212° F., contacting the cooled mixture with additional liquid anhydrous hydrogen fluoride while maintaining a pressure sufficient to maintain the solvent and hydrocarbon oil in the liquid phase, permitting the mixture of said oil and liquid hydrogen fluoride to stratify into an aromatic-containing raffinate phase substantially free of sulfur and a sulfur-containing phase, separating said phases and removing the hydrogen fluoride from said phases.
